CLAIM

The ornamental design for a pacifier clip, as shown and described.

DESCRIPTION

FIG. 1 is a bottom, front left perspective view of a pacifier clip showing my new design.

FIG. 2 is a left side elevation view thereof.

FIG. 3 is a right side elevation view thereof.

FIG. 4 is a bottom plan view thereof.

FIG. 5 is a top plan view thereof.

FIG. 6 is a front elevation view thereof; and,

FIG. 7 is a rear elevation view thereof.

In the drawings, the broken lines depict environmental subject matter only and form no part of the claimed design.
